UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

STOCKING OR SOCK AND METHOD OF KNITTING THE SAME.

1,071,100.

Specification of Letters Patent.

Patented Aug. 26, 1913.

Application filed March 13, 1913. Serial No. 753,923.

To all whom it may concern:

Be it known that I, ROBERT W. SCOTT, a citizen of the United States, and resident of Boston, in the county of Suffolk and State of Massachusetts, have invented a certain new and useful Improvement in Stockings or Socks and Methods of Knitting the Same, of which the following is a specification.

10 An object of my invention is to provide a stocking, and especially a man's stocking or sock, having an integrally formed top which shall be durable and comfortable, and which shall be cheap to manufacture and attractive in appearance.

Another object of my invention is to provide a garment of the character indicated which may be knit at a single operation upon a circular knitting machine having a 20 single set of needles.

To these ends my invention comprises the steps constituting the method or art of knitting the fabric, and the fabric produced by the practice of said steps.

25 In the accompanying drawings, Figure 1 is a view showing a stocking embodying my invention; Fig. 2 is a figure in the nature of a diagram showing the steps in the method of knitting one form of said stocking and 30 the structure of the resulting knit fabric; Fig. 3 is a diagram plan of a segment of a circle of needles arranged to knit the fabric of Fig. 2; Fig. 4 is a fragmentary cross section through the fabric of the top and the

35 welt of a stocking made according to my invention; Fig. 5 is a diagram plan of a circle of instruments arranged to knit a stocking having a top with sections three wales wide of solid fabric and intervening runs or ladders of unknit yarn one wale wide; Fig. 6

40 is a diagram similar to Fig. 2 showing the fabric produced by the arrangement of Fig. 5; Fig. 7 is a plan of another arrangement of a circle of needles to knit a welted top 45 and plain body with sections of three adjacent solid wales; Fig. 8 is a view showing the fabric produced by the arrangement of Fig. 7; Fig. 9 is a plan view showing an arrangement for knitting a welted top having

50 solid plain fabric sections four wales wide, and a plain fabric body portion; Fig. 10 is a diagram showing the fabric produced by the arrangement of Fig. 9; Fig. 11 is a diagram showing a segment of a circle of

needles arranged to knit a top having only 55 one-half as many wales as the plain body portion.

The stocking shown is a seamless circular knit fabric which may be such a structure as that familiar in the prior art so far as the 60 leg portion B, the heel, foot and toe are concerned.

I provide my improved stocking with an integral plain fabric top T of solid fabric having therein runs or wales of yarn floats x, 65 formed by the omission of knitting at a needle or needles during the knitting upon the needles flanking it at each side. As an end finish against raveling I also provide a short turned welt w formed by knitting 70 upon a recurrent needle or needles of the series of needles and therefore containing a definite number of wales and a less number than the leg portion B. This welt is fastened upon the face of the fabric, and the 75 fabric thereof presents its back or loop instead of its face or wale side outwardly.

The fabric structure which will now be described in connection with the steps in the method of forming it, is particularly designed to enable its production upon automatic machinery at a continuous operation, although the steps of the method and the 80 production of the article may readily be practised and attained by the use of hand- 85 operated instruments or machines.

Referring now to Fig. 2, I have shown at I a section of a series of needles or instruments which may be taken as representative of a portion of the needles of a knitting machine viewed in plan and standing in a straight line. Assuming the said needles to be arbitrarily divided into a series of threes I begin the production of the stocking by retiring from action the adjacent needles 1 and 2 throughout the circle, and by feeding to the remaining needles 3 an initial yarn a, which may be locked upon the faces of the needles 3 by reason of the projection in front of it of the needles 1 and 2, to enable 95 the needles 3 to initiate knitting with certainty. I have shown needles upon which no knitting is done at the time represented by their position in the fabric of the various figures in solid black, and the active 100 needles as open circles.

In Fig. 3 I have indicated a segment of the needles arranged as in a circular knit-

ting machine but in the same order as those of Fig. 2; and showing their coöperating instruments, which may be long jacks *j* and short jacks *s*, for determining the sorting of the needles into active and inactive series, but which instruments, for the purpose of practising my method, may essentially consist only of means capable of use to determine the action or inaction of the respective

10 needles at different times in the procedure.

As shown at II, I now feed a course *b*, having first restored to action all of the needles 2, leaving the needles 1 out of action. In this course *b*, needles 2 and 3 both take yarn.

15 Before the next course, the needles 2 are again retired from action, but they are caused to retain their loops, and upon feeding of the third course *c* only the needles 3 will knit, the yarn floating over the spaces 20 represented by the needles 1 and 2.

By the described operation so far, the courses *a* and *b* form a selvage or beginning course of the nature of the first two courses shown in Fig. 2 of my Patent No. 1,045,621, 25 dated November 26, 1912, but it will be seen that by the present operations I secure the engagement of the initial course with every third needle instead of every alternate needle, when the arrangement is that of 30 Figs. 2 and 3. I now proceed to knit a sufficient number of courses, shown for example merely as four, to form the welt *w* by the operation of the needles 3 only. I find that, having begun the structure with a selvage, 35 and having retained loops in other wales than those employed to knit the welt fabric, I am enabled to knit a durable and properly finished welt upon only one-third of the needles. If the extent is sufficiently short and

40 the size of the yarn and the length of the loops are properly gaged, such a welt is of a good appearance and of sufficient lateral elasticity. The withheld loops in the wales of the needles 2 are indicated at *y* in Figs.

45 2 and 4, but it will be understood that for purposes of clearness in said diagram, Fig. 2, said loops are shown greatly elongated, whereas in practice the stitches comprising them are relatively of the same size as the 50 loops in the knit fabric, as will be apparent from Fig. 4. Having knit sufficient fabric upon the needles 3 to form the welt, said needles 3 are retained in action to knit standing wales *g* of a succeeding section of 55 fabric for the top *T* of the stocking, and the needles 2 which are adjacent to said needles 3 are now restored to action, drawing their primary loops *z* through the loop *y* held in 60 their hooks to cast off the welt, all as illustrated at III, Fig. 2. Thus it will be seen that the initial course *d* of the section *T* is 65 knit by the needles 2 and 3 of each group, and that said course contains loops in continuation of the standing wale *g* from the

T, the initial loop of the knit wale from the needle 2 impaling and locking down the withheld or uniting stitch *y* of the second course of the welt. Knitting is now continued upon said needles 2 and 3 for the desired extent of the section *T*, which thus is formed of plain fabric having solid sections two wales wide separated by floats or runs of yarn *x* one wale wide at the location and of the same effect as elongated sinker 70 wales joining adjacent needle wales. The elasticity of the yarn causes said runs or floats to bow toward the back of the fabric in a manner familiar to knitters, thus giving the section *T* a pleasing ribbed appearance and causing it to have less width than the leg *B*, which is knit upon all of the needles. I may, however, provide increased elasticity to enable the garment to be stretched by increasing the length of the loops in the section *T*, and it is within my invention to employ different yarns for the welt *w*, and for the section *T* and for the remainder of the garment. A sufficient length of the section *T* having been formed, 75 I may now place in action the needles 1, which heretofore have performed no part in the operation. As indicated at IV in Fig. 2, all of the needles are now in action and solid plain knitting is initiated at the course *e*, 80 which contains initial loops in the wales from the needles 1, in continuation of the wales occupied by the floats or runs *x*. Solid plain knitting upon all of the needles is now 85 performed in a manner well known in the art for the leg *B*, the heel, foot and toe portions of the stocking. 90

Referring now to Figs. 5 and 6, and to Figs. 7, 8, 9 and 10, it is sometimes desirable to provide a relatively greater extent 105 of fabric in the wales of the top section *T* than is produced by the arrangement of Fig. 2, in which two wales of knitting are flanked by one wale of dropped or floated yarns. When the number of needles is divisible by four, as in the case of Fig. 7, I may provide for three wales of knitting, and one unknit wale by the arrangement shown in Fig. 7, in which the long jacks *j* indicate needles operated to knit at all times 110 and short jacks *s* indicate needles which are operated to knit, but which may be retired from action during the operation of the remaining needles. The needles shown in solid black are in each case those last to 115 be placed into action, and which will not be retired from action thereafter, except at the heel or toe.

Referring particularly to Fig. 7, the long jacks are placed at the needles 2 and 4 and 120 a short jack at the needle 3, and no jack at the needle 1. A first course may be taken in such a manner as to secure a starting selvage structure by first feeding it to the needles 2 and 4 only, the needles 1 and 3 125

65 common to the welt and the section

being projected empty behind the said active needles 2 and 4 as indicated in Fig. 9, which shows the end of the first course. If now a second course *b* is knit by the needles 2, 3, and 4, missing the needle 1, a selvage structure at the wales 2, 3 and 4 will result, but upon attempting to withhold loop 3, the next knitting movements of the needles 2 and 4 will be initiated with respect to the gap at the needle 1, where there is no previous loop, and such needles 2 and 4 will behave as one needle, casting off a long open loop. This fabric is unsatisfactory for all the desired purposes. I may, however, withhold the uniting loops *y* in the second course *b* by the operation of either of the needles 2 or 4 flanking the gap at the inactive needle 1, which it should be noticed has not yet taken yarn. The resulting structure is shown in Fig. 8. It will be seen that, if the needle 2 is selected to be placed out of operation, the initial loop in the wale from the needle 4 occurs in the second course *b*, which is interlocked only with the wales 3. After the third course the wale from needle 4 is otherwise normal, and a welt fabric so made will have half as many wales as there are needles. While the fabric of Fig. 8 is effective for the purposes desired, its construction necessitates different operations with respect to the needle 2 at the first course and the second course, thereby necessitating complexities in the machinery, in the case of machine manufacture, and for such machine manufacture I prefer the arrangement for producing a fabric having the same order of wales and runs *z* shown in Figs. 5 and 6. The needles are again divided into groups of successive fours of which the needle 1 is the last to be entered into operation. One group of needles, 2, 3 and 4 has its even number members supplied with short jacks and its central member 3 supplied with a long jack, while at the next group long jacks are supplied for the needles 2 and 4, and central needle 3 is supplied with a short jack. As before the needles with long jacks are projected to take the yarn of the first course, the needles 1 and those needles 2, 3, and 4 which have short jacks remaining idle and unfed, to be projected before the second course in front of the yarn as shown in Fig. 5, which illustrates the end of the first course. If the number of needles in the circle is a product of the number in a group (in this case four) and an odd number, the desired alternation of the operations at the needles represented by long jacks *j* and short jacks *s* will take place throughout the circle of needles with respect to the gaps created by the idle needles 1, except at one point, which is that illustrated by the uppermost needle 1^a in Fig. 5. At this point two short jacks 1^a *s* will be adjacent to each other across the

gap created by the empty needle 1. I may remedy this by foregoing the making of a ladder or run in the fabric in the wale *h* from said needle 1^a, as shown in Fig. 6, which shows the structures so formed at any selected part of the tube of fabric, the remainder of which will be normal. The needle 1^a may be placed in normal operation by supplying it with a long jack, or by operating it in the same manner as remaining standing wale needles indicated by long jacks *j*. This difficulty, it will be understood, will not occur when the whole number of needles is the product of an even number multiplied by four. 70

It will be noticed in Fig. 5 that the first course is engaged with alternate needles except at the needles 1, where the yarn is passed behind said needle 1 and that needle flanking it which is supplied with a short jack. As in the fabric previously described the operations succeeding the initial course shown in Fig. 5 are in succession to restore all of the needles except the needles 1 to operation for a second course *b*, and thereafter to operate upon needles represented by the short jacks to withhold uniting loops *y*. As a machine operation this may readily be performed by causing the needles having short jacks to retire into their carrier at the yarn feed point upon each revolution of the knitting head; or on each passage of the cams in the case of a straight machine. As in the procedure previously described, when a sufficient length of fabric has been knit upon the standing wales *g* formed at the needles having long jacks *j*, I restore all of the needles having jacks to operation for an initial course *c'* of the top fabric *T*, which initial course will contain loops *z* formed on the withheld or short jack needles, and therefore impaling and casting off each of the loops *y* to initiate another wale of solid fabric. After such a further number of courses have been formed, as may be desired, to constitute the top section *T*, the previously inactive needles 1 will be restored to operation. In order to fill the eyelet hole at the bottom of the omitted needle wales *z*, I prefer to insert the needles 1 during one course, to then retire them during the next succeeding course with their taken loop of yarn still in their hooks, and then to reinsert them to continue in operation to complete a circle of needles for the production of solid plain fabric. In some cases, however, as illustrated in Fig. 2, I may delay this special operation of the needles 1 until after the said needles have taken and knit the yarn for one or more courses thus producing the withheld loops upon the needles 1, in a course *f* for instance, at such wales as are represented by the position of the needles 1. In the fabric of Fig. 2 every third wale will contain the 80

90

withheld-loop or draw stitch structure so made. A course of this character presents an effective stop against the running of drop stitches formed by a hole in the fabric, as pointed out in the patent to L. A. Costello, No. 976,555, dated November 22, 1910. In Figs. 9 and 10 I have illustrated by the same kind of showing as in Figs. 5 and 7 the first course and the arrangement of the 10 needles and their instruments, when it is contemplated to knit a top section T, having four solid wales of plain knitting and one intervening wale of runs or floats *x*. In this case the number of needles to be put 15 into operation for the top T is an even number, and an alternation of needles to be actuated for the first or selvage course is readily possible by providing each group with alternate long and short jacks. As in 20 the case of Fig. 5 one recurring series of uniting loops *y* will be formed in a wale flanking the wale from an inactive needle 1, and others in internal wales of the solid parts of the top fabric T.

25 In Fig. 11 I have illustrated a segment of a circle arranged for a top section T having only half as many wales as the body portion, upon which a welt may be knit in a manner similar to the remaining examples given. 30 The top T of the fabric knit when the operations are those indicated by Fig. 11 will, however, require to be knit of long, loose stitches to provide sufficient lateral elasticity. It will be noticed from inspection 35 of Fig. 11 that the order of operations indicated therein by the arrangement of the jacks *j* and *s* is such as to cause a tying loop *y* to be withheld at every fourth wale. In any of the forms of the fabrics above 40 illustrated the fabric of the short welt *w* may without detriment to the appearance or utility of the garment be knit with sufficiently long loops and of a sufficiently large yarn to render it as elastic laterally as the fabric 45 of the section T following it. I have indicated the relative length of the welt *w* in Fig. 1, but its relative length may be greatly varied, from a few courses to sixty or more, depending upon the relative proportions desired.

50 While I have shown the continuous series of needles employed to knit a seamless stocking corresponding to my invention as arranged in circles, it will be obvious that 55 such continuous series might comprise two straight series of needles near each other; for instance as in the familiar Lamb knitting machine.

It will be seen that I have provided a 60 garment of excellent appearance and utility which may be rapidly knit upon a type of machinery requiring little attendance to the great decrease of the cost of the garment as compared with a stocking having a transferred top of the character heretofore known

in the art. I have at the same time provided by the device of the top section T for the retention of the traditional appearance of ribbed stockings, which is of value to the garment as an article of commerce and 70 of advantage to it as an article of wear.

Aside from the advantage of continuous manufacture flowing from my process and attached to its product, each of the stockings disclosed presents a distinct economy of 75 yarn over a stocking provided with a ribbed top, in which more yarn is included necessarily than in the plain fabric section T. I may thus knit the entire top and body of 80 silk or other superior yarns, or of cotton plated with silk, without the serious additional cost attached to making the whole structure of a ribbed top of such a yarn. When a plated fabric is desired, the structure of the top T presents no obstacle to 85 plating such as is inherently present in a ribbed structure.

What I claim is:—

1. As a new article of manufacture a sock or half hose having an integral top in which 90 there are longitudinal rows or wales of unknit yarn separating plain fabric sections, and an integral welt engaged at one end with some of the wales of the solid fabric of the top section, and continuous with other 95 wales of said section.

2. A stocking having in succession a welt, a top portion and a body or leg portion, the fabric of the welt containing a certain number of wales, said top portion containing a 100 greater number of wales in recurrent predetermined groups, and including wales continuous with those of the welt, and said body portion containing a greater number of continuous adjacent wales including wales continuous with those forming the other sections of the fabric.

3. A stocking having in integral succession a welt, a top portion and a body or leg portion, the fabric of the welt containing a 110 certain number of recurrent separated wales, said top portion containing recurrent knit wales in the aggregate of a greater number than those of the welt, and the body portion of solid plain fabric having therein a greater 115 number of wales than the top portion, some of said wales having initial draw stitches.

4. A stocking having a body portion of plain knit fabric formed in integral prolongation of a section of fabric comprising 120 groups of wales of solid plain knitting separated by floats or runs of yarn, said section of fabric being in integral prolongation of a welt having a selvage course and a subsequent course containing loops each impaled by an initial loop of one of the wales of each of said sections of solid plain fabric.

5. As a new article of manufacture, a circular knit stocking having in succession a 125 welt comprising recurrent wales continuing 130

- into wales of the top of the stocking, said welt having a course of uniting loops in engagement with the initial stitches of certain other wales of the top portion of the 5 stocking, and a plain fabric body or leg in integral prolongation of said top portion having an initial course containing stitches engaging a course preceding the next previous course.
- 10 6. A stocking having a body portion of plain knit fabric formed in integral prolongation of a section of fabric comprising groups of wales of solid, plain knitting separated by floats or runs of yarn, one of the 15 wales being a standing wale in integral prolongation of the knit loops of a welt having a selvage course and a subsequent course containing loops connecting two adjacent standing wales, and impaled by an initial 20 loop of one of the wales of each of said sections of solid plain fabric.
7. A circular knit stocking having a welt, a top section, and a body portion and comprising standing knit wales common to all 25 sections of fabric, said welt having uniting stitches in a course subsequent to its initial course, and said top section having wales adjacent to the standing wales whose initial loops are drawn through said uniting 30 stitches, said body portion having a course near its junction with the top containing loops withheld during an intervening course.
8. A knit fabric or article having in integral succession a turned welt, a top section 35 of plain fabric continuous with said welt containing a certain number of knit wales, and a solid, plain fabric body portion containing more knit wales than said top section.
- 40 9. A knit fabric or article having in integral succession a turned welt, a top section of fabric containing lines or runs of yarns formed at an unemployed needle, and a solid, plain fabric body portion, said welt section 45 having therein fewer wales of knit loops than said body portion and tying or uniting stitches engaged with the loops of certain of the wales of said top section.
10. The art of knitting a stocking having 50 a welt, a top and a body portion at a continuous operation upon a continuous series of instruments which consists in first feeding yarn at recurrent instruments only, in thereafter feeding yarn and forming loops 55 at each of the instruments first fed, and at one or more adjacent instruments, in thereafter withholding some of the loops at the instruments which have been employed, during the formation upon the remaining 60 instruments so far in use of fabric for a welt; and then knitting at only those instruments which have heretofore been employed, including those upon which a loop has been withheld, to form a section containing runs 65 or floats of free yarn opposite the unused instruments, and thereafter knitting a leg and other portions of a stocking at all of said instruments.
11. The art of knitting a stocking having a welt, a body portion and heel, foot and toe 70 portions at a continuous operation upon a circle of instruments which consists in first feeding yarn at recurrent instruments only, thereafter feeding yarn and forming loops at continuous recurrent groups of said instruments, omitting an intervening instrument or instruments, and thereafter withholding some of said loops at certain recurring instruments of said groups during the formation upon the remaining instruments 75 of said groups of fabric for a welt; in then knitting upon all of the needles of said groups of instruments, including those upon which a loop has been withheld to form a section containing runs or floats of free 80 yarn, and thereafter knitting a leg, heel, foot and toe.
12. The art of knitting a stocking consisting of first forming a selvage structure, withholding loops of a course of said structure subsequent to its initial course, and thereafter knitting a welt containing wales of loops less in number than the loops in the final course of the selvage structure, and thereafter knitting a top section of fabric 85 containing more wales than the welt fabric, said step including the formation of an initial course of said top section having loops impaling the withheld loops of the selvage structure; and thereafter knitting solid 90 plain fabric having a greater number of wales than said top section for the leg of the stocking.
13. The art of knitting a stocking having 95 in integral succession a welt, a top portion 100 and a leg and foot, upon a continuous series of instruments, which consists in first forming a starting or selvage course of loops of yarn upon recurrent members only of recurrent groups of said instruments separated 105 by intervening instruments, said intervening instruments receiving no yarn; in then forming a new course and casting off the starting course upon all of the instruments of said recurrent groups; in then withholding 110 the loops upon one or more of the instruments only of each of said groups during the formation upon the remainder of the instruments of said groups of fabric for a welt, in thereafter forming an initial 115 course and successive courses of fabric for the top portion, upon all of the instruments of said groups only, the operation including casting off the terminal stitches of the welt and said withheld loops; and in thereafter 120 knitting the leg and foot upon all of said instruments, including the intervening instruments hitherto unused.
14. The art of knitting a stocking having 125 in integral succession a welt, a top portion 130

and a leg and foot upon a continuous series of instruments, which consists in first forming a starting or selvage course of loops of yarn upon recurrent members only of recurrent groups of said instruments separated by intervening instruments, said intervening instruments receiving no yarn; in then forming a new course and casting off the starting course upon all of the instruments of said recurrent groups; in then withholding the loops upon one or more of the instruments only of each of said groups during the formation upon the remainder of the instruments of said groups of fabric for a welt; in thereafter forming an initial course and successive courses of fabric for the top portion upon all of the instruments of said groups only, the operation including casting off the terminal stitches of the welt and said withheld loops; and in thereafter knitting the leg and foot upon all of said instruments, including the intervening instruments hitherto unused, the operation including the formation upon and withholding upon said intervening instruments of

loops during the knitting of one or more courses upon the remaining instruments.

15. The art of continuously knitting a stocking having a welt section, a top section and a body section upon a series of spaced instruments, which consists in knitting said sections in succession at recurrent like groups in said series of one or more of said instruments, the knitting of the welt being performed at groups separated by a plurality of instrument-spaces; knitting for the top section being performed at groups separated by a less number of instrument-spaces, and knitting for the body portion being performed at contiguous groups forming together an unbroken series of instruments.

In testimony whereof, I have signed my name to this specification in the presence of two subscribing witnesses.

ROBERT W. SCOTT.
